UNITED STATES PATENT OFFICE

CHARLES T. HAWLEY, OF HOLDEN, MASSACHUSETTS, ASSIGNOR TO MOORE FABRIC COMPANY, OF PAWTUCKET, RHODE ISLAND, A CORPORATION OF RHODE ISLAND

PRODUCTION OF NARROW CURVILINEAR ELASTIC FABRIC

Application filed March 1, 1929. Serial No. 343,672.

This invention relates to the weaving of curvilinear elastic fabric and relates more particularly to the production of such fabric in a narrow ware loom.

5 It is the general object of my invention to provide improved mechanism for weaving curvilinear elastic fabric and an improved method of operation thereof by which such fabric may be rapidly and economically produced and by which it may be provided with an inherent and permanent curvilinear set.

10 My invention further relates to arrangements and combinations of parts which will be hereinafter described and more particularly pointed out in the appended claims.

15 One form of mechanism adapted for the carrying out of my invention is shown in the drawings, in which the figure is a perspective view of parts of a narrow ware loom on which 20 curvilinear elastic fabric may be woven by my improved process.

25 Referring to the drawing, which is more or less diagrammatic, I have shown such parts of a narrow ware loom as are necessary to disclose and explain my invention.

I have shown a breast beam 10, and a lay 11 provided with guide blocks 12 for a narrow ware shuttle (not shown) and with a reed 13 which is preferably graduated, with 30 the dents placed more closely together toward the left hand end, as viewed in the drawing.

I have also shown a plurality of harnesses 15, and a warp guide-roll 17 positioned substantially at the rear of the harnesses. Elastic warp threads W are supplied from a cylindrical warp beam 20, rotatably mounted and provided with a suitable friction device 22.

40 Non-elastic binder warps B are supplied from a tapered or conical warp beam 30, also rotatably mounted and provided with a friction device 32. The warp threads W and B pass from the warp beams over a guide-bar 34 and through an assembly reed 35 to the guide-roll 17.

45 The woven fabric F passes over a guide-roll 40 on the breast-beam 10, which guide-roll may be tapered as indicated in the drawing. The fabric F then passes around a

cylindrical take-up roll 50 and a cylindrical guide-roll 51 and is wound up on a conical or tapered cloth roll 52. The roll 50 is mounted on a shaft 54, which is positively driven.

55 The usual mechanism is provided for raising and lowering the harnesses and for reciprocating the shuttle.

50 Production of curvilinear elastic fabric by the mechanism described is accomplished as follows:—

60 As the weaving progresses, the woven fabric is drawn downward at a substantially uniform rate throughout its width by the cylindrical take-up roll 50, and the rubber warp threads W are supplied at a uniform rate of 65 feed and under substantially uniform tension or retardation from the cylindrical warp beam 20.

65 The binder warps B are drawn off of the tapered or conical warp beam 30 against the 70 retarding effect of the friction device 32. Obviously the warp threads at the larger end of the warp beam 30 will be fed more rapidly from the revolving warp beam than the threads at the smaller end, and will thus 75 be under less tension as they are presented at the weaving point. The tight binder warps from the small end of the beam 30 will be bound closely about the elastic warp threads W with which they are associated, 80 while the slack binder warps from the large end of the warp beam 30 will be more loosely bound about their associated elastic warp threads W.

85 It is the custom to weave all elastic warp threads in such fabric in stretched or elongated condition and it is found that the more loosely the elastic warp threads W are bound into the fabric, the greater will be their shrinkage or contraction when released from 90 the weaving tension. Accordingly, the narrow fabric produced as above described will assume a curvilinear set when freed from the take-up roll 50, with the tight binder threads from the small end of the beam 30 95 disposed at the long edge of the curvilinear fabric.

100 This curvilinear effect will be produced to a certain extent if the reed 13 is uniformly graduated throughout its length, but the ef-

fect is materially increased if a graduated reed is used by which the warp threads are crowded toward that edge of the fabric where the more strongly tensioned binder warp threads are found. The crowding of the warp threads laterally still further prevents contraction of the threads when the fabric is released.

This method of weaving a curvilinear elastic fabric has been found very satisfactory in use and the fabric is produced with substantially the same speed and economy as straight fabric of similar width.

Having thus described my invention and the advantages thereof, I do not wish to be limited to the details herein disclosed, otherwise than as set forth in the claims, but what I claim is:—

1. In a narrow ware loom, in combination, a single cylindrical warp beam for elastic warp threads, a single tapered warp beam for non-elastic binder warp threads, weaving mechanism, and a take-up device by which the entire width of fabric is taken up at substantially uniform speed with the elastic warp threads under substantially uniform tension and with the binder warps decreasing in tension toward the larger end of the tapered warp beam, whereby a curvilinear set is given to said fabric.

2. In a narrow ware loom, in combination, means to supply elastic warp threads at a uniform rate and under uniform tension, means to supply binder warps at a rate relatively decreasing toward one edge of the fabric, weaving mechanism, and means to take up the woven fabric at a uniform rate throughout its width.

3. In a narrow ware loom, in combination, means to supply elastic warp threads at a uniform rate and under tension, means to crowd the warp threads more closely together toward one edge of the fabric, means to supply binder warps at a rate relatively decreasing toward the more closely crowded edge of the fabric, weaving mechanism, and means to take up the woven fabric at a uniform rate throughout its width.

4. In a narrow ware loom, a single cylindrical warp beam to supply elastic warp to a piece of curvilinear elastic fabric, a single tapered warp beam to supply non-elastic binder warps for said piece of fabric, weaving mechanism, and a cylindrical take-up roll for the woven fabric, whereby the elastic warps will be more closely bound into the fabric at the edge thereof corresponding to the smaller end of said tapered warp beam.

5. In a narrow ware loom, a single cylindrical warp beam to supply elastic warp to a piece of curvilinear elastic fabric, a single tapered warp beam to supply non-elastic binder warps for said piece of fabric, means to crowd the warp threads more closely together toward the smaller end of said tapered

warp beam, weaving mechanism, and a cylindrical take-up roll for the woven fabric whereby the elastic warps will be more closely wound into the fabric at the edge thereof corresponding to the smaller end of said tapered warp beam.

6. In a narrow ware loom, means to supply uniform lengths of elastic warp threads to a piece of fabric, means to supply binder warp threads progressively increasing in length toward one edge of the fabric, weaving mechanism, and take-up mechanism acting uniformly on all parts of the fabric.

7. In a narrow ware loom, means to supply uniform lengths of elastic warp threads to a piece of fabric, means to supply binder warp threads in lengths progressively increasing toward one edge of the fabric, means to crowd the warp threads together toward the edge where the shorter lengths of non-elastic warp threads are supplied, weaving mechanism, and take-up mechanism acting uniformly on all parts of the fabric.

8. The method of weaving a piece of narrow curvilinear elastic fabric which consists in supplying elastic warp threads at a uniform rate of feed and under substantially uniform tension throughout the width of the fabric, providing non-elastic binder warp threads at a rate of feed gradually increasing toward one edge of said piece of fabric, inserting filling in said fabric, and taking up said fabric at a uniform rate throughout its width.

9. The method of weaving a piece of narrow curvilinear elastic fabric which consists in supplying elastic warp threads at a uniform rate of feed and under substantially uniform tension throughout the width of the fabric, providing non-elastic binder warp threads at a rate of feed gradually increasing toward one edge of said piece of fabric, crowding the warp threads toward the edge of the fabric where the binder warps have the less feed, inserting filling in said fabric, and taking up said fabric at a uniform rate throughout its width.

In testimony whereof I have hereunto affixed my signature.

CHARLES T. HAWLEY.
